UNITED STATES PATENT OFFICE.

HUGO TIRMAN, OF CLEVELAND, OHIO, ASSIGNOR TO BENJAMIN PATTERSON, OF SAME PLACE.

TRACK-SANDING DEVICE FOR LOCOMOTIVES.

SPECIFICATION forming part of Letters Patent No. 557,724, dated April 7, 1896.

Application filed December 7, 1895. Serial No. 571,352. (No model.)

To all whom it may concern:

Be it known that I, HUGO TIRMAN, a citizen of the United States, and a resident of Cleveland, county of Cuyahoga, and State of Ohio, have invented certain new and useful Improvements in Track-Sanding Devices for Locomotives, of which the following is a specification, the principle of the invention being herein explained and the best mode in which

10 I have contemplated applying that principle, so as to distinguish it from other inventions.

The annexed drawings and the following description set forth in detail one mechanical form embodying the invention, such detail 15 construction being but one of various mechanical forms in which the principle of my invention may be used.

In said annexed drawings, Figure I represents a transverse section of a sand-box for 20 a locomotive embodying my invention; Fig. II, a view of the sand-valve mechanism with the front cover and spring-actuated follower removed, and Fig. III an axial section of the sanding device.

25 The sand-box A is provided with a screen a at its feed-opening, which opening is closed by a cap a'. Said screen serves to separate all pebbles, lumps, or other large objects which would be liable to obstruct or interfere 30 with the work of the valves. The bottom a² of the sand-box has an upward bulge, whereby the sand is directed toward two sand-outlet pipes a³, one at each side of the box. Two valve-casings B are secured, one at each side 35 of the base A' of the sand-box, and said valve-casings are each formed with an inlet b, which connects with the outlet-pipe of the sand-box, and an outlet b', which has a sand-pipe C connected to it, by means of which pipe the 40 sand is conveyed from the valve-casing to the track. A funnel-shaped hot-air collector D is secured beneath the apex of the upwardly-bulging bottom of the sand-box within the hot-air chamber formed between the top of 45 the boiler and the bottom of the sand-box, in the base of the latter, and two pipes d extend from said hot-air collector to the outlets of the valve-casings, so as to supply hot air to the sand-pipes and thereby prevent their being 50 clogged during cold weather by snow,

frozen sand, or other frost obstructions. The valve-casing has a diaphragm b², which forms a normally open passage b³ at the upper part of the valve-casing, and a lower passage b⁴, which is closed by a sliding valve E, which 55 has a seat against said diaphragm. The valve is constructed to slide in the casing, and has a rod e, which projects through a stuffing-box b⁵ in the side of the casing. A lever E', to which a cord or rod extending from the locomotive-cab may be secured, is pivotally connected to the valve-rod, so that the valve may be slid over the lower passage or away from it. A follower e' bears against a rib e² upon the back of the slide-valve, and a spring e³, 60 incased in a box b⁵, formed upon the inner face of the cover B' of the valve-casing, bears against the follower, by which means the valve is held against its seat with a yielding pressure. A pipe-coupling F is provided 65 upon the upper side of the valve-casing to the rear of the diaphragm, and said pipe-coupling has a jet-opening f into the upper portion of the interior of the valve-casing, which opening is controlled by means of a 70 valve f'.

The pipe-coupling derives a supply of air under pressure from suitable pipe connection to the air-pump or air-reservoir of the locomotive, and such pipe connection is usually 75 provided with controlling-valve mechanism within convenient reach of the engineer with- 80 his cab. As this pipe connection and valve mechanism form no part of the present in- 85 vention, it is not necessary to further de- scribe or to illustrate the same in this con- nection.

When sand is to be applied to the rails in normal quantities, the air-blast is started, and said blast will cause the sand to eddy up- 90 ward and to fly through the upper opening in the diaphragm, whence it will drop through the valve-casing and sand-pipe to the rail. When a large quantity of sand is required, the valve is drawn open, and a direct passage 95 for the sand, through the valve-casing, is pro- vided.

Other modes of applying the principle of my invention may be employed for the mode herein explained. Change may therefore be 100

made as regards the mechanism thus disclosed, provided the principles of construction set forth respectively in the following claims are employed.

5 I therefore particularly point out and distinctly claim as my invention—

1. In a track-sanding device for locomotives, the combination of a sand-box, sand-pipes, a hot-air chamber between the box and 10 boiler-top, a funnel-shaped hot-air collector in said chamber, and pipes extending from said collector into the sand-pipes, substantially as set forth.

2. In a track-sanding device for locomotives, the combination of a casing having a 15 sand-inlet and a sand-outlet, a diaphragm in said casing and between the inlet and outlet and formed with an upper and a lower passage, an air-jet opening in the upper portion 20 of the casing and at the inlet side of the diaphragm, and a valve movable over the lower

passage of the diaphragm, substantially as set forth.

3. In a track-sanding device for locomotives, the combination of a casing having a 25 sand-inlet and a sand-outlet, a diaphragm having an upper and a lower passage and arranged between the inlet and the outlet, an air-jet opening in the upper portion of the casing and at the inlet side of the diaphragm, 30 a valve sliding over the lower opening of the diaphragm and a spring-pressed follower bearing against the back of said valve, substantially as set forth.

In testimony that I claim the foregoing to 35 be my invention I have hereunto set my hand this 20th day of November, A. D. 1895.

HUGO TIRMAN.
